UNITED STATES PATENT OFFICE.

ROBERT BUTTERWORTH, OF SOMERVILLE, ASSIGNOR OF ONE-HALF TO THE
REVERSIBLE COLLAR COMPANY, OF BOSTON, MASSACHUSETTS.

SUPPLEMENTAL BOSOM.

SPECIFICATION forming part of Letters Patent No. 371,668, dated October 18, 1887.

Application filed July 5, 1887. Serial No. 243,342. (No model.)

To all whom it may concern.

Be it known that I, ROBERT BUTTERWORTH, of Somerville, in the county of Middlesex, State of Massachusetts, have invented a certain new and useful Improvement in Bosoms, of which the following is a description sufficiently full, clear, and exact to enable any person skilled in the art or science to which said invention appertains to make and use the same, reference being had to the accompanying drawings, forming part of this specification, in which—

Figure 1 is a perspective view of my improved bosom; Fig. 2, a plan view of the band detached and opened; Fig. 3, a front elevation of the body of the bosom detached from the band; Fig. 4, a plan view showing the flange turned up to receive the band; Fig. 5, an end view of the body, showing the flange in position to receive the band; and Fig. 6, a diagram showing the method of uniting the parts.

Like letters and figures of reference indicate corresponding parts in the drawings.

In the manufacture of false bosoms, more especially those composed of paper or cloth-faced paper, much difficulty has heretofore been experienced in preventing the body of the bosom from wrinkling or puckering at or near the neck portion after the band is attached, and also in so forming and connecting the band and body as to prevent the exposure of raw or unfinished edges and cause the bosom to fit perfectly.

My invention is designed to obviate these difficulties or objections, and to that end I make use of means which will be readily understood by all conversant with such matters from the following explanation.

In the drawings, A represents the body of the bosom, and B the band, these parts being composed of paper or cloth-faced paper. A curved piece is cut from the upper portion of the body, to adapt it to fit the neck of the wearer, in the usual manner. A curved folding crease or indentation, x, is then made in the upper portion of the body, to assist in forming the flange m, said crease being approximately in parallelism with the curved upper edge of said body and at a distance therefrom corresponding with the width of the flange it is desired to produce.

To prevent the flange from puckering and enable it to be bent outwardly at an angle to the body, a series of slits, f, are cut in it, as best seen in Figs. 3 and 5. A piece is also cut centrally from the edge of the flange, to form an opening, d, for the collar stud or button when the band is attached. 55

The band B consists of a long slightly-curved strip composed of the same material as the body A, and provided with a centrally-arranged crease, i, which usually extends its entire length, as best shown in Fig. 2, but may stop short of the ends of the band, if desired, said crease dividing it into two members or halves, 60 a a. The band is also provided with a pair of stud or button holes, t, at each end, and another pair, v, at the center, the members of each pair of said holes being so arranged with respect to each other as to register when the band 65 is folded lengthwise through the center. 70

In attaching the band to the body the flange m is turned up at an angle to the body, as shown in Figs. 4 and 5. The band is then folded on the crease i and placed over the flange m, as 75 shown in Fig. 6, the members or halves a a composing the band being pressed closely together by hand or in any other convenient and suitable manner, after which the band is firmly attached to the body of the bosom by a row or 80 series of stitches, g, which are passed through both of the members a a of the band and through the flange m, the stitching being extended to the ends of the band, in order to unite said members at or near their free or outer 85 edges, as shown in Fig. 1. The edges of the band from its ends to the points t may, however, be stitched together before inserting the flange m in the band, if preferred, the flange being subsequently inserted and stitched 90 thereto, as shown and described; or, if preferred, the central portion of the band may be stitched to the flange and its ends left to be subsequently stitched.

The band being curved and double and the 95 flange m curved and slit, as described, it will be obvious that the bosom will thereby be prevented from wrinkling or puckering around the neck portion and the raw edges of the flange and band covered or concealed, the upper edge of the band when attached to the bosom being uncut or smooth; also, by curving 100

the band it will fit the neck of the wearer much better than a straight one would.

I do not confine myself to providing the band B with the crease *i*, or to constructing the body 5 or band of any special material; neither do I confine myself to attaching the band to the body by stitches, as it may be pasted or cemented thereto and the edges of the band beyond the bosom cemented together, if desired.

10 Having thus explained my invention, what I claim is—

In a bosom of the character described, the

body A, provided with the curved flange *m*, having the slits *f*, in combination with the curved band B, provided with the stud or button holes *l v*, said band being folded over said flange and its members attached thereto and to each other at or near their free edges by the row or series of stitches *g*, substantially as described.

ROBERT BUTTERWORTH.
